DESIGN.

—o—
H. C. BASCOM & F. RITCHIE.
COOKING STOVE.

No. 20,105.

Patented Aug. 26, 1890.

UNITED STATES PATENT OFFICE.

HENRY CLAY BASCOM, OF LANSINGBURG, AND FRANCIS RITCHIE, OF TROY,
ASSIGNORS TO THE HANGING ROCK STOVE COMPANY, OF HANGING
ROCK, NEW YORK.

DESIGN FOR A COOKING-STOVE.

SPECIFICATION forming part of Design No. 20,105, dated August 26, 1890.

Application filed July 28, 1890. Serial No. 360,221. Term of patent 7 years.

To all whom it may concern:

Be it known that we, HENRY CLAY BASCOM and FRANCIS RITCHIE, citizens of the United States, residing, the said BASCOM at the village of Lansingburg, county of Rensselaer, and State of New York, and the said RITCHIE at the city of Troy, in said State and county, have invented and produced a new and original Design for Cook-Stoves, of which the following is a specification, reference being had to the accompanying drawing, forming part thereof, and consisting of a single figure, affording a view in perspective of our newly-designed stove.

The leading feature of our design consists in the ornamentation of the various parts. A is the base of the stove, and A' the legs. The base on one side is provided with ornamental raised portions, consisting of ribs forming the two wave-line ribs A², respectively extending from the middle portion to the ends of such base, one rib to one end and the other rib to the other end. The wave-line ribs each have a foliated scroll terminal A⁴ about midway between the main terminal scrolls. The legs are provided on their upper ends with a pair of similar scrolls A⁵, each of which is connected by a foliated marginal rib A⁶, extending down the side of the leg, with a smaller scroll terminal A⁷ near the lower end of the leg.

The oven-door B is provided with a central shield-like ornament B', having on the upper sides plain marginal ribs B² and on the other sides foliated marginal scroll-shaped ribs B³, also inner foliated ribs B⁴, parallel with the marginal ribs, and a circular rib B⁵ in the middle of the shield-like ornament.

What we claim as new, and desire to secure by Letters Patent, is—

1. The ornamental design for a cook-stove herein shown and described, consisting of raised portions forming on the base two wave-line ribs, respectively extending from the middle portion to the ends of such base, one rib to one end and the other rib to the other end, each rib having foliated scroll terminals, and a branch with a similar scroll terminal located between the main terminal scrolls and forming on the legs and oven-door foliated scrolls. 45

2. In a design for a cook-stove, the ornamental design on the oven-door herein shown and described, consisting of raised portions forming a shield-like ornament outlined on the upper sides by plain marginal ribs and on the other sides by foliated scroll-shaped ribs having inner foliated ribs parallel with the marginal ribs, and a circular rib in the middle of the shield-like ornament. 55

3. In a design for a cook-stove, the ornamental design for the legs herein shown and described, consisting of raised portions forming on their upper ends a pair of foliated scrolls, each of which is connected by a foliated marginal rib extending down the side of the leg, with a smaller scroll terminal near the lower end of the leg. 60

In testimony whereof we have hereunto set our hands this 25th day of July, 1890.

H. CLAY BASCOM.
FRANCIS RITCHIE.
